LIQUID DISPENSER

Joseph Varga, Cleveland, Ohio, assignor to Albert
J. Ganim, Shaker Heights, Ohio

Application June 24, 1946, Serial No. 678,860

2 Claims. (Cl. 222—500)

1

This invention relates to bottle closures and particularly to the type having a gravity actuated combination dispensing and closure valve, and is hereinafter referred to as a liquid dispenser.

The primary object of this invention is to provide a liquid dispenser that forms an air tight seal, with no vent or liquid opening exposed, when in its closed condition.

Another object is to provide a device of the type stated that will deliver liquid until a glass or similar receiver is filled to within a predetermined distance from the top, whereupon the flow of liquid will cease.

A further object is to provide a device that will waste no liquid through dripping, but will drain all of the unpoured liquid back into the bottle or container.

Other objects are to provide a liquid dispenser that has only one moving part; that is easily dismantled and cleaned; and that is neat and attractive in appearance.

These and still other objects of the invention will become apparent from a reading of the following specification and claims, together with the accompanying drawing, in which like parts are referred to and indicated by like reference characters and wherein:

Figure 1 is a perspective view of the liquid dispenser constituting this invention showing it mounted in a conventional bottle neck in its closed condition;

Figure 2 is a sectional view taken substantially along the line and in the direction of the arrows 2—2 of the Figure 1;

Figure 3 is an enlarged perspective view of the unmounted device in its tilted or open condition;

Figure 4 is a sectional view taken substantially along the line and in the direction of the arrows 4—4 of the Figure 3;

Figure 5 is a cross-sectional view taken substantially along the line and in the direction of the arrows 5—5 of the Figure 3; and

Figure 6 is an enlarged bottom view of the liquid dispenser illustrated in Figure 2.

The instant invention consists broadly of the body member 11 and valve member 25 combined to form the liquid dispenser illustrated in Figure 1, as it appears in its closed position when mounted on a conventional bottle 8.

In its preferred form the device is made of aluminum machined and shaped as illustrated in the accompanying drawing, although any other suitable metallic or plastic material, or combination thereof, may be used that will not be corroded by the contained liquid.

The body 11 is made of a single piece of metal shaped as illustrated, with a tapered axial hole or air vent tube 19. The wide end of the tapered hole 19 terminates in the frusto-conical valve

seat 18. The narrow or bottom end of the hole 19 has a series of longitudinal air vents or slots 16, which are about $\frac{1}{4}$ inch long.

The outer surface of the body 11 has the configuration shown in the Figure 1; and has a top tube 17 joined to the body 11 through the shoulder 15; and the bottom tube 13 joined to the body at the flange 12. The bottom tube has a threaded end 14. A sleeve 34 of cork, or other resilient material, is mounted on the bottom tube as illustrated in Figures 2, 3, 4 and 6.

The threads 14 serve to anchor the sleeve, and the flange 12 limits its upward movement on the tube 13. The valve is also of one piece construction and consists of a hollow stem 21 having a diameter that will cause it to engage the small end of the hole 19 in a free sliding fit and terminating in a solid ball head 25, having a frusto-conical valve face 26 which matches and fits the valve seat 18.

A plurality of liquid delivery holes 23 are bored at the base of the valve face and connect with the inner duct of the hollow stem 21.

The stem has a circumferential groove 22 spaced about $\frac{1}{4}$ inch from its bottom end, which receives the ring shaped spring 31, which has an external diameter greater than that of the hole 19.

The valve stem tube 21 is inserted in the body hole 19 and the spring 31 is placed in the groove 22. Since the spring 31 has an outside diameter greater than that of the hole 19, it acts as a locking means which limits the travel of the stem 21 and also prevents the stem 21 from falling out of the hole 19 when the liquid dispenser is inverted.

In use the liquid dispenser is mounted on a bottle as shown in Figure 1. The cork sleeve 34 forms an air tight seal between the bottle and the bottom tube 13, while the flange 12 limits the depth, the device can be pushed into the bottle opening.

In the position illustrated in Figure 1 the force of gravity causes the valve stem tube 21 to travel downward until the valve face 26 seats itself on the valve seat 18 and then holds it there. This results in an air-tight seal between the valve seat and face which seals off the contained liquid from the exterior and prevents evaporation.

When the bottle is tilted causing the device to assume the position indicated in Figures 3 and 4, the valve stem 21 moves forward until stopped by the circular spring 31 coming in contact with the end of the bottom tube 13 as illustrated in Figure 4. The contained liquid flows through the hollow stem tube 21 and out through the liquid delivery holes 23.

It will be noted that at the same time the valve stem 21 assumes a position on the lower face of the tapered body hole 19 which leaves an air

vent passage 24 in the wide part of the tapered hole. This air passage is continued past the narrow end of the hole, which serves as a bearing surface for the stem 21 by means of the slotted air vents 16 as shown in Figures 4, 5 and 6.

The air needed to equalize the pressure inside and outside of the bottle enters through this passage way to replace the dispensed liquid, thus assuring a smooth flow of liquid at all times.

When the bottle is returned to its vertical position as illustrated in Figures 1 and 2, the valve falls back into the body, closing the opening and causing any liquid in the hollow stem 21 to drain back into the bottle.

If either of the shoulders 15 or 12 are placed on the edge of the glass, or other receiver, and the bottle rested on it, as the liquid is being poured, the flow will cease as soon as the liquid rises in the glass high enough to cover the end of the air vent tube 19. Thus by varying the position of the shoulders in relation to the outlet end of the air vent tube 19, the height of the dispensed liquid can be determined ahead of time and be exactly duplicated every time the liquid is dispensed. With the dispenser illustrated, having two shoulders 15 and 12, a choice of two heights of liquid is available; however, any desired number of spaced shoulders can be used in order to adapt the device to a variety of special purposes.

Since this liquid dispenser has only two parts, which can be easily taken apart by removing the spring 31 from its seat 22, it is easy to clean and keep sanitary at all times.

It will now be clear that there is provided a device which accomplishes the objectives heretofore set forth. While the invention has been disclosed in its preferred form, it is to be understood that the specific embodiment thereof as described and illustrated herein is not to be considered in a limited sense, and there may be other forms or modifications of the invention which should also be construed to come within the scope of the appended claims.

I claim:

1. A liquid dispenser of the type adaptable for use in the outlet of a liquid container and mounted on the brim thereof, comprising in combination, a substantially cylindrical body member having a frusto-conical valve seat at the normally upper end thereof and having a tapered axial channel therethrough, the large end of which intersects the said valve seat and the small end of which has a plurality of spaced longitudinal slots in the wall thereof forming an air vent, the said body member also having an external flange therearound engageable with the brim of the container and having an external shoulder spaced from the said flange and capable of engaging the edge of a liquid receiver when in an inverted position and determining the height the dispensed liquid will assume in the receiver, and a valve member slidably mounted in the said axial channel and capable of assuming a first position

when the body member is in a normally upright position and of assuming a second position when the body member is tilted, the said valve member having a straight stem portion and a substantially spherical head portion on the normally upper end thereof, the said stem portion having a longitudinal liquid duct therethrough, and having a plurality of radial liquid outlets proximate the said head portion opening in the said duct, the 10 said head portion having a frusto-conical face thereon engageable with the said valve seat when the body member and stem portion are in a normally upright position.

2. A liquid dispenser of the type adaptable for 15 use in the outlet of a liquid container and mounted on the brim thereof, comprising in combination, a substantially cylindrical body member having a frusto-conical valve seat at the normally upper end thereof and having a tapered axial 20 channel therethrough, the large end of which intersects the said valve seat and the small end of which has a plurality of spaced longitudinal slots in the wall thereof forming an air vent, the said body member also having an external flange 25 therearound engageable with the brim of the container and having an external shoulder spaced from the said flange and capable of engaging the edge of a liquid receiver when in an inverted position and determining the height the dispensed 30 liquid will assume in the receiver, and a valve member slidably mounted in the said axial channel and capable of assuming a first position when the body member is in a normally upright position and of assuming a second position when the 35 body member is tilted, the said valve member having a straight stem portion and a substantially spherical head portion on the normally upper end thereof, the said stem portion having a longitudinal liquid duct therethrough, and having a 40 plurality of radial liquid outlets proximate the said head portion opening in the said duct, the said head portion having a frusto-conical face thereon engageable with the said valve seat when the body member and stem portion are in a normally 45 upright position, the said radial liquid outlets being spaced from the body member valve seat a distance sufficient to prevent the flow of air through the axial channel from interfering with the flow of liquid through the said duct when 50 the dispenser is in the inverted position.

JOE VARGA.
